FLUID-DRIVEN PUMP

Fred A. Lane, Shelburn, Ind., assignor to Lane Motors, Inc., Terre Haute, Ind., a corporation of Indiana

Original application December 18, 1942, Serial No. 469,386. Divided and this application April 15, 1946, Serial No. 662,202

6 Claims. (Cl. 103—44)

1

The present invention relates to pumps, and more particularly to double acting, high efficiency, high pressure pumps of novel construction.

The primary object of the invention is to provide a pump of the character described which shall be an improvement over pumps heretofore known. Another object of the invention is to provide a pump in which moving parts will be reduced to a minimum, packing will be unnecessary, and the application of power to the fluid to be pumped will be effected through a rotary cam. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a longitudinal section through a pump constructed in accordance with my invention;

Fig. 2 is a transverse section taken substantially on the line 2—2 of Fig. 1;

Fig. 3 is a transverse section taken substantially on the line 3—3 of Fig. 1; and

Fig. 4 is a flat projection of the rotary cam forming an element of my invention.

Referring more particularly to the drawings, it will be seen that I have illustrated a housing 100, formed to provide a cylindrical chamber 101 at one end of which is formed a socket 102 receiving an anti-friction bearing 103 forming a journal support for one end of a shaft 104, the opposite end of which is journalled in an anti-friction bearing 105 carried in a suitably formed socket 106 in a closure head 107 for the opposite end of the cylinder. A disc 108, having an external periphery such as to fit snugly within the chamber 101, is fixed or keyed to one end of the shaft 104, and is formed at one point in its periphery with a radial notch 109. A similar disc 110, having a similar notch 111, is fixed or keyed to the shaft 104 at the opposite end of the cylinder 101; and a spacer sleeve 112 is secured to said discs 108 and 110.

Splined on said spacer sleeve 112 is a piston 113 formed with a cam track indicated generally by the reference numeral 114; and the foot 115 of a follower 116 oscillably mounted in a projection 117 of the housing 100 is operatively engaged in the said cam groove 114. Said cam track is preferably of the form illustrated in Fig. 4, com-

2

prising a continuous groove extending three times about the periphery of the piston 113 and comprising a first reach 49 extending from the right-hand end of the piston as viewed in Fig. 1 to the left-hand end thereof within a peripheral extent of 270°; a return reach 50 extending from the left-hand end of the piston to the right-hand end thereof within a peripheral extent of 270°; a second advancing reach 51 extending from the right-hand end of the piston to the left-hand end thereof within a third peripheral extent of 270°; and a second return reach 52 extending from the left-hand end of the piston to the right-hand end thereof within a fourth peripheral extent of 270°. It will thus be seen that three complete rotations of the shaft 104 will produce two complete cycles of reciprocation of the piston 113; while the discs 108 and 110 will also turn through three rotations.

Associated with one end of the housing 100 is a series of radially projecting cylinders 119, 119a, 119b, 119c, and 119d. Since the assemblies associated with these cylinders are identical, only one will be described.

25 A port 120 provides communication between the interior of the cylinder 119 and the interior of the cylinder 119; but said port is located in registry with the disc 108 which, at all times except when the notch 109 registers with said port, 30 masks or closes the port 120. Reciprocably mounted within the cylinder 119 is a piston 121 having a reduced piston projection 122 reciprocable in the reduced cylinder 123. A control valve assembly 124 is secured to the mouth of the cylinder 123, said unit providing an inlet passage 125 controlled by a check valve 126 and an outlet passage 127 controlled by a check valve 128.

35 Associated with the opposite end of the housing 100 is a series of radially projecting cylinders 129, 129a, 129b, 129c, and 129d. Since the assemblies associated with the cylinders of the 129 series are identical only one will be described.

40 A port 130 provides communication between the interior of the cylinder 101 and the interior of the cylinder 129, but said port is arranged in registry with the disc 110 which, at all times except when the notch 111 registers with the port 130, masks and closes said port.

45 A piston 131 is reciprocably mounted within the cylinder 129 and is provided with a reduced piston extension 132 reciprocable in a reduced cylinder 133. With said cylinder 133 is associated a 50 control unit 134 comprising an inlet passage 135

controlled by a check valve 136 and an outlet passage 137 controlled by a check valve 138.

Relief means must preferably be provided in association with each of the cylinders of the 119 series and with each of the cylinders of the 129 series to facilitate operation of the pistons 121, etc., and 131, etc., therein. Thus, each cylinder of the 119 series is formed in its outer end with a port such as the port 187, and each cylinder of the 129 series is similarly formed in its outer end with a port such as the port 188. Obviously, the provision of these ports in the cylinders of the two series will prevent such entrapment of fluid above the pistons of the 121 series and the pistons of the 131 series as would interfere with their operation. Preferably, but not necessarily, the port like the port 187 of each cylinder of the 119 series will be connected with the port like the port 188 of the corresponding cylinder of the 129 series by a conduit like the conduit 189, so that fluid expelled from the cylinder 119, for instance, as the piston 121 is driven upwardly, will be forced through the port 187, conduit 189, and port 188 to assist in effecting the downward movement of the piston 131.

Of course, all of the inlet passages 125 and 135 are suitably connected to one or more sources of fluid to be pumped, while all of the outlet passages 127 and 137 are suitably connected to one or more points of use of fluid under pressure.

As the piston 113 moves from its illustrated position toward the left, during clockwise rotation of the shaft 104, as viewed from the right, fluid contained in the left-hand end of the cylinder 101 will be forced through the notch 109 and port 120 into the cylinder 119 to elevate the piston 121. Such movement of the piston 121 forces the piston 122 upwardly in the cylinder 123. Initial movement of the piston 122 will close the check valve 126 and open the check valve 128, and continued movement of the said piston will force fluid out of the cylinder 123 through the outlet passage 127 to the point of use. As the piston 121 reaches the upward limit of its stroke, the notch 109 will move out of registry with the port 120 and into registry with the corresponding port of the cylinder 119a, whereupon the piston within said cylinder 119a will be similarly operated, while the piston 121 is held in its elevated position by the fluid entrapped within the cylinder 119 by the closure of the port 120 by the peripheral surface of the disc 108.

During such movement of the piston 113 toward the left, fluid will first be drawn from the interior of the cylinder 129 through the port 130 and the registering notch 111 into the right-hand end of the cylinder 101, thus drawing the piston 131 downwardly to draw the piston 132 downwardly. Such movement of the piston 132 will close the check valve 138 and open the check valve 136 to draw fluid into the cylinder 133 through the inlet passage 135. At the moment when the piston 131 has reached the lower limit of its stroke, the notch 111 will move out of registry with the port 130 and into registry with the port 130a, whereupon further movement of the piston 113 toward the left will cause operation of the piston within the cylinder 129a in the same manner.

This application is a division of my co-pending application Serial No. 469,386 filed December 18, 1942, upon which issued Patent 2,411,438 on November 19, 1946.

I claim as my invention:

1. Pumping mechanism comprising a cylindri-

cal housing, a shaft mounted for rotation with a portion thereof within said housing, a series of radially-disposed cylinders peripherally grouped about said housing and each communicating with the interior of said housing adjacent one end of the latter through a port, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders peripherally grouped about said housing and each communicating with the interior of said housing adjacent the opposite end of the latter through a port, a second valve disc fixed on said shaft within said housing in closing relation to said last-mentioned ports, said second valve disc being formed with a notch in its peripheral surface providing, when in registry with one of said last-mentioned ports, communication between the associated cylinder and the interior of said housing, a valved inlet and a valved outlet for each cylinder of each series, independent of said ports, a piston axially reciprocable in said housing between said discs, and means for converting rotation of said shaft into reciprocation of said piston.

2. Pumping mechanism comprising a cylindrical housing, a shaft mounted for rotation with a portion thereof within said housing, a series of radially-disposed cylinders peripherally grouped about said housing and each communicating with the interior of said housing adjacent one end of the latter through a port, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders peripherally grouped about said housing and each communicating with the interior of said housing adjacent the opposite end of the latter through a port, a second valve disc fixed on said shaft within said housing in closing relation to said last-mentioned ports, said second valve disc being formed with a notch in its peripheral surface providing, when in registry with one of said last-mentioned ports, communication between the associated cylinder and the interior of said housing, a valved inlet and a valved outlet for each cylinder of each series, independent of said ports, a piston axially reciprocable in said housing between said discs, a continuous cam groove formed in the peripheral surface of said piston, and means supported by said housing against movement axially of said housing and engaging in said cam groove to convert rotation of said piston into reciprocation thereof.

3. Pumping mechanism comprising a cylindrical housing, a shaft mounted for rotation with a portion thereof within said housing, a series of radially-disposed cylinders peripherally grouped about said housing and each communicating with the interior of said housing adjacent one end of the latter through a port, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders, peripherally grouped about said housing and each communicating with the interior of said housing, a valved inlet and a valved outlet for each cylinder of each series, independent of said ports, a piston axially reciprocable in said housing between said discs, and means for converting rotation of said shaft into reciprocation of said piston.

terior of said housing adjacent the opposite end of the latter through a port, a second valve disc fixed on said shaft within said housing in closing relation to said last-mentioned ports, said second valve disc being formed with a notch in its peripheral surface in peripheral registry with the notch in said first disc and providing, when in registry with one of said last-mentioned ports, communication between the associated cylinder and the interior of said housing, a valved inlet and a valved outlet for each cylinder of each series, independent of said ports, a piston axially reciprocable in said housing between said discs, and means for converting rotation of said shaft into reciprocation of said piston.

4. Pumping mechanism comprising a cylindrical housing, a shaft mounted for rotation with a portion thereof within said housing, a series of radially-disposed cylinders peripherally grouped about said housing and each communicating with the interior of said housing adjacent one end of the latter through a port, a piston reciprocable in each of said cylinders and operatively associated with the plunger of a pump assembly, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders peripherally grouped about said housing and each communicating with the interior of said housing adjacent the opposite end of the latter through a port, a piston reciprocable in each cylinder of said second series and operatively associated with the plunger of a pump assembly, a second valve disc fixed on said shaft within said housing in closing relation to said last-mentioned ports, said second valve disc being formed with a notch in its peripheral surface providing, when in registry with one of said last-mentioned ports, communication between the associated cylinder and the interior of said housing, a piston axially reciprocable in said housing between said discs, a body of fluid entrapped in said housing and in said cylinders between each end of said last-named piston and the adjacent ends of the pistons in said series of cylinders, respectively, and means for converting rotation of said shaft into reciprocation of said piston.

5. Pumping mechanism comprising a cylindrical housing, a shaft mounted for rotation with a portion thereof within said housing, a series of radially-disposed cylinders peripherally grouped about said housing and each communicating with the interior of said housing adjacent one end of the latter through a port, a piston reciprocable in each of said cylinders and operatively associated with the plunger of a pump assembly, each of said cylinders being provided with a relief port in that portion thereof remote from its first-mentioned port, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders peripherally grouped about said housing and each communicating with the interior of said housing adjacent the opposite end of the latter through a port, a piston reciprocable in each cylinder of said second series and operatively associated with the plunger of a pump assembly, 75

assembly, each of the cylinders of said second series being provided with a relief port in that portion thereof remote from its first-mentioned port, a second valve disc fixed on said shaft within said housing in closing relation to said last-mentioned ports, said second valve disc being formed with a notch in its peripheral surface providing, when in registry with one of said last-mentioned ports, communication between the associated cylinder and the interior of said housing, a piston axially reciprocable in said housing between said discs, a body of fluid entrapped in said housing and in said cylinders between each end of said last-named piston and the adjacent ends of the pistons in said series of cylinders, respectively, and means for converting rotation of said shaft into reciprocation of said piston.

6. Pumping mechanism comprising a cylindrical housing, a shaft mounted for rotation with a portion thereof within said housing, a series of radially-disposed cylinders peripherally grouped about said housing and each communicating with the interior of said housing adjacent one end of the latter through a port, a piston reciprocable in each of said cylinders and operatively associated with the plunger of a pump assembly, each of said cylinders being provided with a relief port in that portion thereof remote from its first-mentioned port, a valve disc fixed on said shaft within said housing in closing relation to said ports, said valve disc being formed with a notch in its peripheral surface providing, when in registry with one of said ports, communication between the associated cylinder and the interior of said housing, a second series of radially-disposed cylinders peripherally grouped about said housing and each communicating with the interior of said housing adjacent the opposite end of the latter through a port, a piston reciprocable in each cylinder of said second series and operatively associated with the plunger of a pump assembly, each of the cylinders of said second series being provided with a relief port in that portion thereof remote from its first-mentioned port, conduit means connecting the relief port of each cylinder of said first series with the relief port of a corresponding cylinder of said second series, a second valve disc fixed on said shaft within said housing in closing relation to said last-mentioned ports, said second valve disc being formed with a notch in its peripheral surface peripherally so related to the notch in said first disc that said disc notches register simultaneously with cylinders whose relief ports are connected, providing, when in registry with one of said last-mentioned ports, communication between the associated cylinder and the interior of said housing, a piston axially reciprocable in said housing between said discs, a body of fluid entrapped in said housing and in said cylinders between each end of said last-named piston and the adjacent ends of the pistons in said series of cylinders, respectively, and means for converting rotation of said shaft into reciprocation of said piston.
